UNITED STATES PATENT OFFICE.

CLARENCE WATSON WHITE, OF NORTH BENNINGTON, VERMONT, ASSIGNOR TO H. C. WHITE COMPANY, OF NORTH BENNINGTON, VERMONT, A CORPORATION OF VERMONT.

WAGON GEAR.

Application filed September 30, 1921. Serial No. 504,322.

To all whom it may concern:

Be it known that I, CLARENCE WATSON WHITE, a citizen of the United States, residing at North Bennington, in the county of 5 Bennington and State of Vermont, have invented new and useful Improvements in Wagon Gears, of which the following is a specification.

My invention relates to vehicle frames, 10 having reference more specifically to the construction of the connecting means between the running gear and the front bolster of light wagon gears and has for an object to produce a form of swivel connection that 15 is strong and durable and effects a more permanent connection between the parts referred to.

The accompanying drawings forming a 20 part of this specification illustrate in the different views a preferred form of my improvement which is herein described in detail, the invention however residing in the broader conception of the essential parts substantially as shown.

25 Referring to the drawings, Figure 1 is a front elevation of a child's vehicle to which an embodiment of my improvement is applied;

Fig. 2 is a partial plan view of the swivel 30 mechanism; and

Fig. 3 is an elevation of the same, partially in section, taken on line 3—3 of Fig. 2.

Having reference to the drawings, the 35 numeral 1 represents a familiar four wheeled type of child's coaster wagon having a body 2 supported by spring members 3 front and back, the front member 3 being supported by a bolster piece 4 made of a small piece of channel iron which in turn is pivotally connected to the front axle 5 by means of 40 the bolt 10 that corresponds to and performs the functions of the king-pin in an ordinary wagon structure.

A channel bar 6 is secured in an inverted 45 position upon the axle rod 5 and these two parts together form the axle proper. A disc 22 is secured firmly to the upper face of the inverted channel at a point midway between the wheels, so as to move with the axle proper 50 in all swivel movements. A similar disc 20 is secured to the under face of the bolster channel 4 and in superimposed relation to and in contact with the disc 22. The bolt 10 is secured in any suitable manner to the axle

rod 5 and inverted channel 6, passes upwardly through aligned apertures in the superimposed discs 20 and 22, through the bolster channel 4, and has a threaded free end.

A brace strap 16 which is secured to the body of the wagon extends downwardly over 60 and rests upon the bolster channel 4. The pin 10 passes through an aperture in the brace 16, and a nut 25 threaded upon the upper or free end of the pin 10 serves to clamp the brace to the bolster and the latter with its attached disc to the axle and its attached disc.

The upper end of the bolt 10 need only be threaded down to the level of the extension 70 16 or the top surface thereof, and has upon its threaded end the horizontal nut 25 which has a locking means comprising a plurality of radially disposed longitudinally cut notches 26 for the reception of a cotter pin 28, a hole 27 of substantially the same size 75 as the width of the openings 26 having been provided in the bolt 10 at a predetermined height for the reception of the pin 28.

The position of the orifice 27, longitudinally considered, is such that it will contain 80 the cotter pin 28 within the notches 26 of the nut 25 and the notches are of sufficient depth to permit a slight margin of adjustment of the nut to maintain in suitable relationship the extension 16 operably upon the bolster 85 piece 4.

The discs 20 and 22 preferably have tongues 90 24 struck out therefrom and bent into embracing relation with the channels to which they are attached so as to assist in effecting a secure connection between each disc and its channel. The discs are also preferably provided with corresponding annular corrugations 21 and 23 which nest in one another 95 and resist displacement of one laterally over the face of the other.

Thus it will be seen I have provided simple, durable and effective means for connecting the front part of the body to the axle of a vehicle wherein the parts are rendered readily accessible, and easily detachable should the necessity arise for disconnecting the axle from the swivel mechanism, which results may be accomplished and the parts again returned to their normal arrangement and adjustment with accuracy and promptitude by the employment of my improved mechanism.

Having described my invention, what I claim is:

1. In a vehicle, a front axle rod, a rolled channel strip secured in an inverted position upon said rod, a stamped metal disc secured upon the upper face of the channel centrally thereof, a body part, a rolled channel strip carried by the body part, a stamped metal disc secured to the under face of the last named channel and resting upon the first named disc, and a pivot pin passing through both channels and discs for securing them together.
2. The construction for vehicles substantially as set forth in claim 1, in which the sheet metal discs are provided with integral stamped corresponding annular corrugations that nest in one another and are concentric with the pivot pin.
3. In a vehicle, an axle, a body part, a pair of sheet metal discs arranged face to face and secured one to the body part and the other to the axle, and means for confining the discs together for relative rotation upon one another, said discs having integral stamped nesting corrugations in their abutting faces.
4. In a vehicle, an axle, a body part, a pair of sheet metal discs arranged face to face and secured one to the body part and the other to the axle, and means for confining

the discs together for relative rotation upon one another, the discs having struck out tongues embracing the portions of the body part and the axle to which they are secured. 35

5. In a vehicle, a front axle rod, a channel secured in an inverted position upon said rod, a sheet metal disc secured upon the upper face of the channel centrally thereof, a body part, a channel carried by the body part; a sheet metal disc secured to the under face of the last named channel and resting upon the first named disc, and a pivot pin passing through both channels and disc for securing them together and permitting relative 45 rotation of the discs, each disc having struck out tongues embracing the channel to which it is secured in order to effect a more secure connection between them.

6. In vehicles having a swivel axle and bolster thereon, a disk attached to said axle, having an annular groove in the face thereof; a similar disk attached to said bolsters having a ridge corresponding to the groove and adapted to fit slidably therein; a bolt secured to said axle and having a threaded end passing through said bolster; a nut on said bolt; and means for locking said nut at predetermined positions on said bolt. 50

In testimony whereof I have hereunto set 55 my hand.

CLARENCE WATSON WHITE. 60
